UNITED STATES PATENT OFFICE.

GUSTAV I. WEIGELIN, OF FRANFORT, GERMANY.

IMPROVEMENT IN DRYING-KILNS.

Specification forming part of Letters Patent No. 147,718, dated February 17, 1874; application filed June 11, 1873.

To all whom it may concern:

Be it known that I, GUSTAV I. WEIGELIN, of Frankfort, Empire of Germany, have invented a new and useful Improvement in Drying-Kilns; and I do hereby declare the following to be a full, clear, and exact description thereof, which will enable those skilled in the art to make and use the same, reference being had to the accompanying drawing forming part of this specification, in which drawing—

Figure 1 is a vertical central section of this kiln. Fig. 2 is a horizontal section of the same. Fig. 3 is a sectional top view thereof. Fig. 4 is a transverse section in the plane $x x$, Fig. 1. Fig. 5 is a similar section in the plane $y y$, Fig. 1.

Similar letters indicate corresponding parts.

This invention relates to a kiln for drying and evaporating the moisture from earthenware, bricks, glue, wood, peat, starch, linen, wool, and other articles, by means of the radiating heat of a hot-air pipe, which is placed beneath the floor of the drying-room, and by these means the articles in said room are uniformly heated and dried, and the vapors and gases which are emitted by the articles during the drying process are driven off through a discharge-pipe by ventilating the drying-chamber. My invention consists in the arrangement of a heating-pipe beneath the skeleton floor or false bottom of the heating or drying chamber, said pipe being connected with the heating-furnace, which is situated at one end of said drying-chamber in such a manner that the radiating heat of said pipe will uniformly warm and penetrate the articles during the drying process. It consists, further, in the arrangement of a branch pipe projecting from said heating-pipe and serving to connect said pipe with the air-space of the furnace in the next succeeding chamber in such a manner that the heat discharging from one drying-chamber will serve to increase the heat in the next chamber. It consists, further, in the arrangement of ventilating flues or tubes in the top or roof of the drying-chamber, which flues are connected with the heating-furnace, and pass the heated air into the drying-chamber, which serves to ventilate said chamber in such a manner that the steam or gases generated therein are carried off through the discharge-

pipe. This invention consists, further, in the arrangement of a discharge-pipe or flue in the roof of the drying-chamber, which flue is connected with the smoke-flue or chimney of the kiln. The kiln is constructed with a corridor or passage through it, on opposite sides of which are situated the drying-chambers, which are provided each with a separate furnace that is accessible from said corridor.

In the drawing, the letter A designates the drying-chamber, which is hermetically sealed, and which is situated on one side of a corridor, B, on the opposite side of which is a similar chamber, A'. Beneath the floor of the corridor B is formed a smoke-flue, C. In said drying-chambers are placed detachable false bottoms D D, which are composed of an open-work or skeleton frame, so that hot air can circulate freely through them. In each of the chambers A A' is a furnace E, which is provided with a suitable door that opens on the corridor B. Extending downward from the fire-place of the furnace E is a channel, a, Fig. 1, which conducts the products of combustion into a serpentine heating-pipe, F, which is laid beneath the floor of the drying-chamber A, and emerges into the smoke-flue C, being provided with a conical valve or damper, b. In order to utilize and consume all the produced heat, the arrangement has been so made that, instead of passing off at once into the smoke-flue, the heated air will enter, by means of a branch-pipe, H, Fig. 2, into the air-space N of the furnace in a second chamber, and from here in a third, and so on, the air-space N being provided with a cover or damper, c, Fig. 1, to open or close the communication. Over the fire-place of the furnace is an iron arch, d, (best seen in Fig. 4,) above which there is a hollow space, d', that communicates on one side with an air channel or passage, e, which leads out into the corridor B, having a door, f, by means of which it can be closed, and on the opposite side said hollow space communicates with a tube, I, which, passing through the arched top or ceiling of the chamber A and branching off in an opposite transverse direction, as at g g, Fig. 3, leads into flues J J, which serve to ventilate the drying-chamber, being provided with perforations h h, (see Fig. 5,) said ventilating-

flues being situated on opposite sides in the top of the drying-chamber. In the roof of the drying-chamber is situated the discharge-pipe or flue K, which has a number of perforations, *i i*, and which discharges into a flue, L, Fig. 1, that leads downward to the smoke-flue, the discharge being closed, if desired, by means of a conical valve or damper, *j*. The fresh air entering the air-channel *e* is heated in passing through the hollow space *d'* by the radiating heat of the iron arch *d*. The air thus heated enters the drying-chamber through the perforations *h h* in the ventilating-flue *J*, and it evacuates by means of the perforations *i i* in the discharge-flue *K*, and, in order to insure a uniform supply and discharge of the hot air, the size of the perforations varies with their distance from the openings in the flues. A thermometer is placed in the drying-chamber, visible from the corridor *B*, so that the temperature of said chamber can be ascertained and regulated at all times.

The articles to be dried are brought in through the door *M*, and are stacked on the floor *D*. The discharge of air from the drying-chamber is then stopped by closing the damper *j*. Then the ventilation of the chamber is stopped by closing the air-channel *e*, thereby cutting off the supply of air. The door *M* is made hollow, and is filled with sand or other suitable material, so as to render it perfectly air-tight, and, said door having been closed, the fire is lighted in the furnace *E*, the products entering the serpentine heating-pipe *F*, as already stated. The heat radiating from said pipe then gradually warms the articles on the floor *D*, and consequently the moisture contained in them evaporates, and not being allowed to escape, the steam in the chamber acquires a certain degree of tension. By these means a chief requirement is attained for drying in a rational manner, the articles being uniformly warmed, which can only take place in a room containing steam under pressure. As soon as the temperature of the chamber has attained the necessary degree for drying, which can be ascertained by means of the thermometer, the discharge valve or damper *j*

is opened. The chamber is then ventilated by opening the air-channel *e*, and the vapors and gases generated will rush out through the discharge-flue, and thereby they are prevented from becoming condensed in the drying-chamber.

What I claim as new, and desire to secure by Letters Patent, is—

1. The heating-pipe *F*, arranged beneath the perforated false bottom *D* and communicating with the furnace *E*, through the opening *a*, in combination with the valve *b* and flue *C*, all constructed and arranged substantially as and for the purpose specified.

2. The heating-pipe *F*, provided with the branch pipes *H* for connecting with the air-spaces *N* of the next succeeding furnace, for the purpose specified, in combination with the valve *b* and flue *C*, substantially as herein shown and described.

3. The ventilating-flues *J* in the top of the drying-chamber, in combination with the flue *I*, having the branching tubes *g g*, and with the heating-furnace *E*, substantially as and for the purpose specified.

4. The furnace *E*, pipe *I*, flues *J*, perforated flue *K*, and flue *L*, in combination with the heating-pipe *F* and chamber *A*, all constructed and arranged substantially as and for the purpose specified.

5. The furnace-arch *d*, space *d'*, air-passage *e*, and flue *I*, having the branch tubes *g g*, in combination with the perforated ventilating-flues *J*, drying-chamber *A*, and pipe *F*, substantially as described.

6. The duplex drying-chambers *A A*, separated by a corridor, *B*, and each provided with a heating-pipe, *F*, and ventilating-pipes *J J*, combined substantially as described, the heating-pipe of one chamber communicating with the air-space *N* of the furnace *E* in the opposite chamber, as and for the purpose specified.

GUSTAV I. WEIGELIN.
